(57) **CLAIM**

The ornamental design for a sign, as shown and described.

DESCRIPTION

FIG. 1 is a front plan view of a sign of the present invention; and,

FIG. 2 is a perspective view of the sign of FIG. 1.

A back view of the sign is not illustrated as it does not form part of the claimed design. In the drawings, the broken lines represent environmental structure forming no part of the claim.

1 Claim, 2 Drawing Sheets

FIG. 1

FIG. 2
